Primary Examiner — Terry A Wallace(74) *Attorney, Agent, or Firm* — Mark D. Bowen; Malin Haley DiMaggio & Bowen, P.A.(57) **CLAIM**

The ornamental design for a cup holder having an electronic display, as shown and described.

DESCRIPTION

FIG. 1 is a right side view of a cup holder having an electronic display in accordance with the present invention with a cup illustrated in phantom view;

FIG. 2 is a front view of the cup holder with electronic display;

FIG. 3 is a rear view thereof;

FIG. 4 is a left side view thereof;

FIG. 5 is a top view thereof;

FIG. 6 is a bottom view thereof;

FIG. 7 is a top front right side perspective view thereof; and,

FIG. 8 is a bottom, rear, left side perspective view thereof. The broken lines illustrating the cup in FIG. 1 are for illustrative purposes only and form no part of the claimed design.
